UNITED STATES PATENT OFFICE.

THOMAS H. B. PIERCE, OF DEXTER, MAINE.

DESIGN FOR A GAME-BOARD.

SPECIFICATION forming part of Design No. 24,701, dated September 24, 1895.

Application filed October 26, 1894. Serial No. 527,097. Term of patent 14 years.

To all whom it may concern:

Be it known that I, THOMAS H. B. PIERCE, a citizen of the United States, residing at Dexter, in the county of Penobscot and State of Maine, have invented and produced a new and original Design for a Game-Board, of which the following is a specification, reference being had to the accompanying drawing, showing the same in outline.

The one figure inclosed within the angles A B C D is all that is deemed necessary to illustrate the design sufficient for a full understanding of the same.

A right-angled parallelogram, slightly longer from top to bottom than from side to side, forms the outside of the whole design. Around this a narrow band A B B C C D D A is marked as a margin. Within the space inclosed by this margin are drawn the two right-angled parallelograms formed by the lines E F, E F, F G, F G, G H, G H, H E, and H E, these figures being of a length twice as great as their width and placed opposite each other—one at the top and the other at the bottom of the figure—so that their sides are parallel with the aforesaid marginal lines and one-half nearer to the top D A and to the bottom B C than to the sides A B and C D. Within each of the parallelograms just described is inclosed a right-angled parallelogram (angles marked I J K L) centrally situated, occupying one-half the width of the outer parallelogram and three-fourths of its length. These figures, marked by the angles E F G H E F G H and I J K L I J K L are each divided into halves longitudinally by the lines M N M N. At the center or middle of the lines F G F G are placed the stars O O, from which radiate the diagonal lines O P, O P and O P O P to a point in the middle of the marginal lines A B C D, (marked P P), these lines O P, O P, O P, and O P inclosing a perfect square set diagonally to the outer sides of the whole figure. Parallel with the lines of the square just described are the diagonal lines reaching from the inner corners of the larger parallelograms E E and H H to the points V V V V in the lines F G and F G, which points are exactly one-half the distance between the stars O O and the angles F and G F and G. Next from the two ends of each line F G and F G lines extend

diagonally within each of the larger parallelograms, meeting at the point S S in the middle of the lines E H and E H. Parallel with the last-described lines and equidistant between them and the angles E E H H lines are drawn connecting the ends of the lines M N M N and the lines E H E H, intersecting the latter at points one-fourth of the distance from their outer ends, and similar lines parallel with O P, O P, O P, and O P are drawn from the ends of the lines M N M N to intersect the lines F G and F G at the points V V V V, which are at one-fourth of the whole length distant from their outer ends. From a point in the middle of the lines J K J K (marked R) lines are drawn at right angles with the diagonals O P, O P, O P, and O P, intersecting the lines F G and F G at the points T T T T, which are at one-fourth the distance between the stars O O and the angles marked F F and G G. From the apex of the angles R R a line is drawn through the apex of the angles S S, connecting the lines J K J K, and parallel with the last-described line two lines are drawn—one upon each side thereof—connecting the lines F G and F G at the points V V V V, which are equidistant between the stars O O and the angles F F and G G. Also from the lines I L I L, at the points marked on the drawing U U U U, lines are drawn to intersect the lines F G F G at the points T T T T, the same being parallel with the line R R and midway between it and the lines V V V V. In the center of the whole figure, inclosed by the angles marked A B C D and in the middle of the line R R, a shaded circle (marked Q) is placed, and two open rings of similar size are drawn, intersecting the same parallel with the lines E H E H.

At points covering every intersection of lines diagonal with the sides A B, B C, C D, and D A upon the figure, as herein described, open rings of the same size as the shaded circle in the center of the figure are placed.

What I claim is—

The design for a game board as herein shown and described.

THOMAS H. B. PIERCE.
